US0D1051928S

(12) **United States Design Patent** (10) Patent No.: **US D1,051,928 S**
(45) Date of Patent: ** Nov. 19, 2024

(54) **DISPLAY SCREEN WITH ICONS**

(71) Applicant: **Express Scripts Strategic Development, Inc.**, St. Louis, MO (US)

(72) Inventors: **James M. Gaines, Jr.**, Wildwood, MO (US); **Nicholas D. Main**, St. Louis, MO (US)

(73) Assignee: **Express Scripts Strategic Development, Inc.**, St. Louis, MO (US)

(**) Term: **15 Years**

(21) Appl. No.: **29/893,428**

(22) Filed: **May 30, 2023**

Related U.S. Application Data

(62) Division of application No. 29/798,520, filed on Jul. 8, 2021, now abandoned.

(57) **CLAIM**

The ornamental design for a display screen with icons, as shown and described.

DESCRIPTION

The sole FIGURE illustrates a front view of a display screen with icons showing the claimed design.

The broken lines in the FIGURE show a display screen and form no part of the claimed design.

1 Claim, 1 Drawing Sheet
